(57) **CLAIM**

The ornamental design for a concrete vibrator body, as shown and described.

DESCRIPTION

FIG. 1 is a front, left and top perspective view of a concrete vibrator body showing our new design;

FIG. 2 is a rear, right and top perspective view thereof;

FIG. 3 is a rear, right and bottom perspective view thereof;

FIG. 4 is a front elevational view thereof;

FIG. 5 is a rear elevational view thereof;

FIG. 6 is a top plan view thereof;

FIG. 7 is a bottom plan view thereof;

FIG. 8 is a left side elevational view thereof;

FIG. 9 is a right side elevational view thereof; and,

FIG. 10 is a front, left and top perspective view thereof illustrating a state in which an environmental structure (a flexible shaft) is attached to the concrete vibrator body.

The broken lines are included for the purpose of illustrating portions of the concrete vibrator body and form no part of the claimed design. The broken lines of FIG. 10 are included for the purpose of illustrating environmental structure and form no part of the claimed design.

1 Claim, 10 Drawing Sheets
